COMPRESSION SUPPORTING DEVICE

Willis W. Lee, Detroit, Mich.

Application May 19, 1933, Serial No. 671,805

1 Claim. (Cl. 128—78)

My invention relates to a new and useful improvement in a surgical appliance adapted primarily in treatment of subluxation or strain of the sacro-iliac articulation. The theory of the treatment of such subluxation or strain of the sacro-iliac articulation is well understood by all physicians, osteopaths, chiropractors, etc. Subluxation or strain commonly results from a misplacement of the ilium, and in the treatment it is necessary to compress both iliac bones into the sacrum by forcing both hips backward towards or into the center of the back. This treatment may be done by manual manipulation, but where the strain or displacement has existed over a prolonged period of time, and in some cases where the displacement is of short duration, the bones have a tendency to resume the disarranged position.

It is an object of the present invention to provide an appliance which may be secured to the body and which will serve as a means for forcing or compressing the iliac bones into the sacrum and at the same time affording means for binding the various parts in their proper position.

It is another object of the present invention to provide an appliance of this class whereby the treatment referred to may be accomplished while at the same time the appliance may be released to permit access to the sacral region for adjustments and treatments when desired.

It is another object of the present invention to provide an appliance of this class which will be easily and quickly applied in position and through which the proper compression may be transmitted to the body for effecting the re-arrangement of the disarranged parts.

Another object of the invention is the provision of an appliance of this class which will permit the patient to relieve the various parts of strain and compression when the use of the same is not desired, as for instance, when the patient is retiring for the night or is assuming for a considerable period of time a position which will take the patient off his feet.

Another object of the invention is the provision of an appliance of this class whereby the amount of compression or strain may be adjusted so that as the treatment continues, the strain may be released from day to day, thus permitting the muscles and joints to gradually and naturally assume their normal functions.

Another object of the invention is the provision of an appliance whereby the strain exerted on both sides of the body is always equalized, thus assuring the proper compression at both sides

of the body and eliminating the possibility of distorting the body into an unnatural form or position.

Another object of the invention is the provision of an appliance whereby the relative strain on the upper edges and lower edges may be adjusted to suit necessary conditions.

Another object of the invention is the provision of an appliance of this class so arranged and constructed that discomfort to the wearer is reduced to a minimum, interference to the thigh when assuming a sitting position is obviated and a hardening or wrinkling of the appliance avoided, while at the same time a cracking or tearing of the skin is eliminated.

Another object of the invention is the provision whereby the sacro-iliac appliance may be positioned on a patient with a minimum amount of time and labor and with the greatest ease and accuracy.

Another object of the invention is the provision of a sacro-iliac appliance whereby a sacrum pad may be used or dispensed with at will without necessitating the complete removal of the appliance.

Other objects will appear hereinafter.

The invention consists in the combination and arrangement of parts hereinafter described and claimed.

The invention will be best understood by a reference to the accompanying drawing which forms a part of this specification, and in which,

Fig. 1 is a perspective view of a portion of a person's body from the rear showing the invention applied.

Fig. 2 is a front elevational view of a person's body showing the invention applied.

Fig. 3 is an inside plan view of the invention.

Fig. 4 is a fragmentary sectional view taken on line 4—4 of Fig. 3.

The appliance comprises a pair of fabric or skin portions 7 and 8, and in this connection it may be noted that experience has shown mole skin to be a very satisfactory material to use for this purpose, and in this specification and claim hereof, the word "fabric" is to be interpreted as to mean such material whether it be of a fabric or woven material as will serve the purposes and functions intended. In the drawing I have illustrated these portions provided with eyelets 9 through which a suitable lacing 10 may be projected. The purpose of the lacing is to provide a means for adjustably connecting these ends of the parts together. The major portion of the body of the fabric portions 7 and 8,

extending outwardly from the lines 11, is covered on the inner face with adhesive material and until used, this adhesive material is covered with a protective layer of gauze 12. This gauze is removed when it is desired to press the adhesive bearing face of the fabric members in engagement with the body. As clearly shown in Fig. 1 and Fig. 3, each of the layers is, at its lower edge, cut inwardly on a curved line as at 13 so that the garment will not press into the hip 14 of the wearer, or wrinkle when the person assumes a sitting position. It will also be noted that the adjacent ends which are laced are extended downwardly on the lower edges so as to, while maintaining a bearing against the body sufficiently high as to cover the sacrum, also extend fairly well downwardly on to the buttocks.

In applying the device the adhesive bearing ends of the portions 7 and 8 are pressed in engagement with the body of the wearer, after the lacing has been let out, so that when the device is applied to the body of the wearer, there is no strain or compression placed upon the body. The free ends of these portions are tapered downwardly to provide a sort of nose as at 15, so that the free ends of these fabric portions reach downwardly and may be applied to the body at a point immediately in front of the pelvic arch or ilium from which the lower edge extends upwardly and cooperates with the other portion to extend across the sacrum. When the device is applied, the physician or attendant placing the appliance on the body, then tightens the adjustable connecting means, which in the present instance is shown as a lacing, until the desired pressure is exerted on the body and the hips are drawn backwardly so as to compress the iliac bones into the sacrum under the proper strain and compression desired. The clearance between the adjacent ends of the portions 7 and 8 is however, when the lacing or a connecting means has been let out, sufficient so that when the desired compression initially placed upon the body by lacing together these adjacent ends is attained, there is still left a space between these adjacent ends. This permits of a subsequent increasing of the compression or a greater flexing of the hips rearwardly as the patient responds to the treatment, and the disarranged parts gradually returned to normal position. This space also permits of adjustment so that when desired, the lacing or connecting means may be drawn tighter at the upper edge or vice versa, thus affording a device which is universal in its applications, both as to the physical peculiarities of the patient and the personal peculiarity of the disarrangement which may have taken place.

It is obvious that because of the fact that the appliance consists of two separate parts which are detachably connected at their rear or adjacent ends, an equalizing of the strain on opposite sides of the body is always present. It is also believed obvious that the patient may, when the compression is not necessary, by releasing the connecting means relieve himself of the strain and thus attain ease while off his feet or when retiring.

It is also believed obvious that a chiropractor, osteopath, or physician may by detaching the adjacent ends and folding the members 7 and 8 backwardly on the lines 11, have access to the sacral region for manipulation or treatment. Because of the formation of the device in a minimum number of parts, its application to the body is an operation which may be very easily and quickly performed, and since but little time is required, it is an operation which the physician himself may do without injury to his dignity or requiring an excessive amount of his time rather than transmitting the work to an attendant or to a nurse.

While I have illustrated and described the preferred form of my invention, I do not wish to limit myself to the precise details of structure shown, but desire to avail myself of such variations and modifications as may come within the scope of the appended claim.

Having thus described my invention what I claim as new and desire to secure by Letters Patent is:

A surgical appliance of the class described comprising: a pair of separate and identical fabric portions of substantially the same width throughout their length, a coating of adhesive material on one of the faces of said portions, said coating extending from one end to a point adjacent the other end to provide an uncoated portion at that end, said coated ends being adapted for attachment to a body above the pelvic bones in spaced relation to each other and said portions then projecting rearwardly around the body to terminate adjacent the sacrum, the uncoated ends being there spaced apart, separate attachment means for connecting said uncoated ends and providing a means for drawing said ends together for compressing the iliac bones into the sacrum, and the lower edges of said portions being curved inwardly intermediate their ends to provide cut-outs to allow said portions to closely conform to the contours of a body.
